The ornamental design for a doghouse, as shown and described.

DESCRIPTION

FIG. 1 is a front, left, and top perspective view of a doghouse, showing my new design;

FIG. 2 is a rear, right, and bottom perspective view thereof;

FIG. 3 is a front view thereof;

FIG. 4 is a rear view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front, right, and top perspective view of the doghouse of FIG. 1 in one state;

FIG. 10 is an enlarged view of an encircled area labeled “10” in FIG. 1;

FIG. 11 is an enlarged view of an encircled area labeled “11” in FIG. 1;

FIG. 12 is an enlarged view of an encircled area labeled “12” in FIG. 1; and,

FIG. 13 is an enlarged view of an encircled area labeled “13” in FIG. 2.
